BOOK PROTECTOR

Julius Bauer, Chicago, Ill.

Application April 4, 1947, Serial No. 739,395

5 Claims. (Cl. 281—34)

1

The present invention relates to improvements in book protectors.

An object of the present invention is to provide an improved book protector provided with means for conveniently marking the pages of a book.

A further object is to provide a book protector which may be used with books having a range of sizes, which book protector is provided with conveniently operable means for marking the pages of a book.

A further object is to provide a combined book cover and page marker employing readily replaceable elastic cord means for marking the pages of a book.

A further object is to provide a combined book protector and page marker which is simple and sturdy in construction, cheap to manufacture and convenient to use.

A further object is to provide an improved book protector and page marker well adapted to meet the needs of ordinary service.

Further objects will appear as description proceeds.

Referring to the drawings—

Figure 1 is a top plan view illustrating one embodiment of the present invention;

Figure 2 is a bottom edge view of the structure illustrated in Figure 1; and

Figure 3 is a sectional view on an enlarged scale taken along the plane 3—3 of Figure 1.

According to the illustrated embodiment of the present invention, a sheet of relatively heavy material may be utilized to provide the back wall, side walls, and the flaps of the book protector. Such a sheet of material is indicated by the numeral 13 and is scored along the lines 18a—18a to provide the back wall 13 and swinging side walls 29—29. The edges of the side walls 20—20 are folded over at the regions indicated by the numerals 21—21 to provide flaps 22—22 adapted to engage the inside surface of the covers of a book. Said flaps lie in approximately parallel relationship with the remainder of their corresponding side walls. The longitudinal edges of the protector are indicated by the numerals 18b—18b. The swinging side edges are defined by the folded over portions 21—21.

Adjacent to the longitudinal free edges 23—23 of the flaps 22—22 are the socket portions 24—24 of separable fasteners adapted to co-operate with the stud portions 25—25 of said separable fasteners, which stud portions are carried by the main portions of the side walls 20—20. Said separable fasteners, consisting of the members 25

2

24—25, are located adjacent to the upper and lower edges of the combined book cover and page marker. Adjacent to each folded edge 21 is a button 26 carried by the corresponding flap 22. A piece of elastic cord 27, having a loop 28 at each of its extremities, is supported at each of its ends by a corresponding fastener portion 24, and is supported at its mid-portion by the button 26.

In using the illustrated embodiment of the present invention, the covers of a book, not illustrated, may be inserted in the pockets provided by the flap 22. Said flaps will engage the covers of the book with sufficient friction to hold the book against accidental displacement. The pages at the left side of the book and the pages at the right side of the book will be held down by the elastic cords 27—27. It will be a simple matter for the reader, when he desires to turn a page, to slip that page out of engagement with the corresponding elastic 27 and slip it under the elastic 27 of the opposite side of the book holder. As long as this practice is followed, the pages of the book will be marked at all times and the book may be closed and opened again without necessity for the reader to think of changing any book marking means.

The invention has the advantage of cheapness of manufacture and has the further advantage that either the lower or the upper portion of each piece of elastic cord 27 may be utilized for ordinary book marking purposes while the upper portion may be utilized for indexing. In other words, with the covers of a book located under the flaps 22—22 between the fasteners 24—25, 24—25 (which carry the loops 28), the upper and lower portions of each elastic cord 27 may be used as book markers, making four book markers in all; that is, the fasteners 24—25, 24—25 are located above and below the respective top and bottom edges of the protected book, leaving the top and bottom portions of each elastic cord 27 available for page marking functions. This advantage is of importance particularly when the reader is studiously reading the book inasmuch as he can conveniently mark any four pages for future reference.

Though a certain preferred embodiment of the present invention has been described in detail, many modifications will occur to those skilled in the art. It is intended to cover all such modifications that fall within the scope of the appended claims.

What is claimed is:

1. A book protector comprising, in combina-

tion, a back wall and two side walls hinged to said back wall, said side walls being provided with flaps, said flaps and said side walls being provided with co-operating separable fastener members adapted to hold said flaps in approximately parallel relationship with their respective side walls to provide pockets for receiving the covers of a book, certain of said separable fastener members being located adjacent to the swinging edges of their corresponding flaps and being provided with holding members, each of said flaps adjacent to the axis of swing of its corresponding flap being provided with another holding member, elastic cord means carried by said holding members, said certain holding members being located adjacent to the tops and bottoms of said flaps whereby they are adapted to lie above and below the respective top and bottom edges of said book covers.

2. A book protector comprising a sheet of material, formed to provide a back wall and swinging side walls, said side walls being hinged to said back wall, said side walls being folded over to provide flaps, said flaps and said side walls being provided with co-operating separable fastener members adapted to hold said flaps in approximately parallel relationship with their respective side walls to provide pockets for receiving the covers of a book, certain of said separable fastener members being located adjacent to the swinging edges of their corresponding flaps and being provided with holding members, each of said flaps adjacent to the axis of swing of its corresponding flap being provided with another holding member, elastic cord means carried by said holding members, said certain holding members being located adjacent to the tops and bottoms of said flaps whereby they are adapted to lie above and below the respective top and bottom edges of said book covers.

3. A book protector comprising a sheet of material, formed to provide a back wall and swinging side walls, said side walls being hinged to said back wall, said side walls being folded over to provide flaps, each of said flaps being provided with holding means and with elastic cord means supported by said holding means, certain of said holding means being located adjacent to the free corners of said flaps and including means for detachably securing said flaps in folded relation-

ship with the remainder of said sheet of material, another of said holding means of each of said flaps being located adjacent to the fold of its corresponding flap.

- 5 4. A book protector comprising, in combination, a sheet of material formed to provide a back wall and side walls, said walls being hinged to said back wall and being folded over to provide flaps, separable fasteners each having a component part thereof located adjacent to a corresponding corner of said flaps and having a corresponding component part secured to a main portion of one of said side walls to detachably hold said flaps in folded relationship with the remainder of said sheet of material, said flaps adjacent to the swinging side edges of the book cover being provided with holding means and elastic cord means supported by said separable fasteners and said holding means.
- 10 5. In combination in a book protector, a sheet of relatively heavy material, said sheet being provided with score lines to provide a back wall, side walls hinged to said back wall and flaps hinged to said side walls, holding means secured to said flaps adjacent to the swinging edges of said side walls and other holding means secured to each of said flaps adjacent to the longitudinal free edges of said flaps and located adjacent to the ends of said edges, and elastic cord means supported by said holding means on each of said flaps.
